United States Patent Office

Des. 186,007
Patented Aug. 25, 1959

186,007

FRONT PANEL FOR A FURNACE

Douglas G. Aitken, Painesville, Ohio, assignor to Hupp Corporation, Cleveland, Ohio, a corporation of Virginia

Application September 11, 1958, Serial No. 52,614

Term of patent 14 years

(Cl. D81—19)

Figure 1 is a perspective view of a front panel for a furnace panel embodying the instant design;

Figure 2 is an enlarged fragmentary front view of a portion of the panel of Figure 1;

Figure 3 is a section taken along line 3—3 of Figure 2; and

Figure 4 is an enlarged section taken along lines 4—4 of Figure 1.

I claim:

The ornamental design for a front panel for a furnace, substantially as shown.
